UNITED STATES PATENT OFFICE.

WILLIAM E. HEATH, OF BALTIMORE, MARYLAND.

DESIGN FOR A BOTTLE.

SPECIFICATION forming part of Design No. 32,118, dated January 23, 1900.

Application filed December 14, 1899. Serial No. 740,361. Term of patent 7 years.

To all whom it may concern:

Be it known that I, WILLIAM E. HEATH, a citizen of the United States, residing at Baltimore, in the State of Maryland, have invented a certain new and useful Design for Bottles; and I do hereby declare the following to be a full, clear, and exact description of the invention, such as will enable others skilled in the art to which it appertains to make and use the same.

This invention relates to a new and useful design for bottles; and the object of my invention is to provide the neck or mouth of a bottle with certain peculiar distinguishing features of utility in this art.

Referring to the accompanying drawings, Figure 1 is a perspective view of a bottle embodying my new and useful design, the body portion of the bottle being indicated generally by dotted lines. Fig. 2 is a longitudinal section through the neck of the bottle. Fig. 3 is a side elevation of the said neck portion of the bottle, the new design embodied in the neck portion of the bottle being indicated by dotted lines as seen through the transparent 25 glass. Fig. 4 is a plan view looking into the open mouth of the neck of the bottle.

In the drawings, a is the neck of a bottle, formed around its open end with the annular seat or recess a' . The interior of the bottle-neck below said seat a' is formed with a cylindrical portion a'' , terminating in the upwardly-facing annular shoulder, seat, or ledge a^3 , and the internal diameter of the bottle-neck is gradually increased below said seat 35 until the normal diameter of the interior of the bottle-neck is reached.

Having thus fully described my invention, what I claim as new, and desire to secure by Letters Patent of the United States, is— 40

The design for a bottle, substantially as described and shown.

In testimony whereof I affix my signature in presence of two witnesses.

WILLIAM E. HEATH.
